VEHICLE LAMP LENS

David O. Chase and Roderick F. Bunyea, Skaneateles, N.Y., assignors to R. E. Dietz Company, Syracuse, N.Y., a corporation of New York

Continuation of design applications Ser. No. 5,683, Feb. 3, 1967, Ser. No. 6,012, Mar. 1, 1967, Ser. No. 6,716, Apr. 14, 1967, Ser. No. 7,148, May 16, 1967, and Ser. No. 7,492, June 16, 1967. This application Dec. 1, 1967, Ser. No. 10,176

Term of patent 14 years

U.S. Cl. D48—32
Int. Cl. D12—14

FIG. 1

FIG. 2

FIG. 3.

FIG. 4.

Fig. 5.

Fig. 6.

FIG. 8.

FIG. 7.

FIG. 6.

FIG. 10.

FIG. 11.

FIG. 12.

FIGURE 1 is a top plan view of a vehicle lamp lens embodying our new design, it being understood that the prisms seen through the lens in the areas at the four corners of the lens outside the circular center area, and which prisms are partially shown in said four corner areas, continue uniformly throughout said four corner areas; and

FIGURE 2 is a side elevational view thereof, it being understood that the diffusion ridges seen through the sides of the lens, and which are partially shown along said sides, continue uniformly along said sides.

FIGURE 3 is a top plan view of a modified form of the lens as disclosed in FIGURE 1, it being understood that the prisms seen through the lens in the tri-cornered areas on three sides of the circular center area, and which prisms are partially shown in said three side areas, continue uniformly throughout said three side areas; and

FIGURE 4 is a side elevational view thereof, it being understood that the diffusion ridges seen through the sides and flattened corners of the lens, and which are partially shown along said sides and corners, continue uniformly along said sides and corners.

FIGURE 5 is a top plan view of another modified form of the lens as disclosed in FIGURE 1, it being understood that the prisms seen throughout the lens in the areas at the four sides of the lens outside the circular center area, and which prisms are partially shown in said side areas, continue uniformly throughout said four side areas; and

FIGURE 6 is a side elevational view thereof, it being understood that the diffusion ridges seen through the sides of the lens, and which are partially shown along said sides, continue uniformly along said sides;

FIGURE 7 is a top plan view of another modified form of the lens as disclosed in FIGURE 1, it being understood that the prisms seen through the lens in the areas at either end of the lens outside the circular

center area, and which prisms are partially shown at either end, continue uniformly throughout said ends;

FIGURE 8 is an end elevational view thereof; and FIGURE 9 is a side elevational view thereof;

FIGURE 10 is a top plan view of still another modified form of the lens as disclosed in FIGURE 1, it being understood that the prisms seen through the lens in the areas at the ends of the lens outside the circular center area, and which prisms are partially shown at one end, continue uniformly throughout said ends;

FIGURE 11 is a side elevational view thereof; and FIGURE 12 is an end elevational view thereof.

This application is a continuation of the following applications: D-6012, filed Mar. 1, 1967; D-5683, filed Feb. 3, 1967; D-6716, filed Apr. 14, 1967; D-7148, filed May 16, 1967; and D-7492, filed June 16, 1967, all now abandoned.

We claim:

The ornamental design for a vehicle lamp lens, substantially as shown and described.
